(57) **CLAIM**

The ornamental design for a solar-powered exhaust fan, as shown and described.

DESCRIPTION

FIG. 1 is a top, side perspective view of the solar-powered exhaust fan;

FIG. 2 is a bottom, side perspective view of the solar-powered exhaust fan;

FIG. 3 is a side elevation view of the solar-powered exhaust fan, with the other sides being a mirror image thereof;

FIG. 4 is a top plan view of the solar-powered exhaust fan; and,

FIG. 5 is a bottom plan view of the solar-powered exhaust fan.

The broken lines shown in FIGS. 2 and 5 are for the purpose of illustrating portions of the solar-powered exhaust fan that form no part of the claimed design.
